COMBINED MICROPHONIC TRANSMITTER AND AMPLIFIER THEREFOR

Application filed July 21, 1927. Serial No. 207,372.

The invention relates to apparatus for reproducing sound, more particularly apparatus of the microphonic type; and it has for its object to associate with a microphone of any well-known or special design amplifying means which will not only materially increase the volume of sound resulting from the actuation of the microphone, but at the same time will furnish conveniently the source of energy necessary in the operation of the microphone and without appreciable distortion of the resulting sound waves. The invention has for its object, furthermore, to so arrange the supply of energy for the microphone that the operation of the amplifier itself is simplified in that it provides at the same time for a biasing of the grid of said amplifier. A further object of the invention resides in the provision of means for varying the volume of the output; also, in the limiting of the voltage across the terminals of the energizing circuits for the microphone, so that objectionable voltages with consequent shocks to one coming in contact therewith will not result when the said energizing circuit is open.

To this end, the invention contemplates connecting the energizing circuit of the microphone in series with the plate circuit of the amplifier, suitable resistances being associated therewith as will hereinafter more fully appear.

The nature of the invention, however, will best be understood when described in connection with the accompanying drawings, in which:

Fig. 1 is a front elevation illustrating a microphone device suitable for use with phonographic records—as one means for actuating the same—and indicated as associated with a one-stage audio frequency amplifier to which it is connected by suitable conductors.

Fig. 2 is a diagrammatic representation of the circuits and connections involved.

Referring to the drawings, 10 designates any suitable apparatus for reproducing sounds and whereby an electric current is varied, for example, a microphone transmitter; and which, as indicated by way of example, may be a sound box of the electric type

having a stylus 11 adapted to engage grooves of a sound record 12 and as is well understood in the art. This box is ordinarily pivoted to a strap having a suitably supported arm 13, and through the latter conductors 55 are led to further apparatus for amplifying and converting the fluctuations in the electric current produced by the microphone into sound waves. The particular microphone herein disclosed, reference being had more especially to Fig. 2 of the drawings, is of the type shown in U. S. Letters Patent No. 1,590,750 to A. P. Pinkler, and comprises the microphone elements 15, transformer 16 and output leads 17 therefrom.

Ordinarily, a source of potential, such as a 1½- or 3-volt battery, is included in the leads 18 of the energizing circuit for the microphone; but in accordance with the present invention, the supply of energy is to be derived from the plate circuit of an audio frequency amplifier 19. The latter may be, generally, of any well-known or standard type embodying the thermionic valve 20, the A-battery 21 for the filament thereof and the B-battery 22 for the plate circuit of said amplifier, also an input transformer 23 and herein indicated as of the auto-transformer type. In place of the A- and B-batteries it will be understood, of course, that suitable rectifiers or so-called A- and B-battery eliminators may be substituted, it being required only that proper voltages be supplied for both the filament circuit and the plate circuit of the amplifier. It is desirable, also, that the impedance of the transformer 23 match that of the transformer 16 of the microphone in order to enhance the efficiency of transformation and obviate distortion.

In accordance with the invention, the plate circuit is interrupted at the terminals 25 and a substantial non-inductive resistance 26 of the order of 1,000 ohms introduced in series substantially at the one terminal, said terminals being adapted to be connected to the leads 18 of the energizing circuit for the microphone. This may conveniently be effected by the double-throw switch 27, the other pair of terminals 28 of which are designed to connect in a secondary source of

potential 29 should it be desired to supply more energy to the microphone than would be obtainable from the plate circuit of the amplifier. It is understood, of course, that 5 for most purposes the plate circuit energy will be ample; but occasion may arise where greater volume is desired and the provision of the double-throw switch 27 permits of conveniently connecting in additional power, as 10 set forth. In the event, however, of opening the switch at the terminals 25, the plate circuit will also be open, and, furthermore, there will be set up across said terminals a substantial potential which might cause ob- 15 jectionable shocks should one operating the apparatus come in contact therewith.

There is, therefore, provided to bridge said terminals a non-inductive resistance 30 of considerably higher value than the resistance 20, for example, of the order of 2,000 ohms; and a connection as the lead 31 is arranged to short-circuit the same when switch 27 is thrown to connect in the battery 29 in order that the grid bias may not become too high. 25 Moreover, during the interval of switching it affords protection in always preventing high voltage leads from extending outside the amplifier. The said resistance will serve, also, to keep the terminal voltages on open 30 circuit comparatively low (less than 50 volts), and as the energizing circuit resistance is comparatively low (say less than 100 ohms) no appreciable current will be taken thereby from the energizing circuit of the microphone. Furthermore, the changing plate 35 current would ordinarily cause distortion by the varying voltages applied to the microphone; but this is largely overcome by the comparatively high resistance 26 and, fur- 40 thermore, there is provided a by-passing condenser 32, for example, of the order of 4 mfd., thus keeping the energizing current for the microphone substantially constant.

It is desirable, also, to provide means for 45 varying the volume of output; and to this end, a variable non-inductive potentiometer 33 ranging from 0 to 50,000 ohms is included across the input transformer 23, the same being regulated by a knob 34 at the front 50 of the amplifier 19 which is provided, also, with a knob 35 for the control of the filament current through resistance 36 in circuit with the filament of the thermionic valve 20.

The foregoing combination thus provides 55 for a simple, compact and self-contained, as well as portable, unit 19 associated with the sound box or microphone member 10; and by the novel arrangement of circuits shown and described, the sound waves reproduced 60 thereby are comparatively free from distortion. Moreover, by matching the impedances of the microphone transformer and amplifier input transformer, the energy required for 65 operating the former is kept comparatively low, thus making for better operation of said

microphone. By matching the impedance of the microphone transformer (one side of which matches the microphone used and the other side matching the average loud speaking device), with the input side of the auto-transformer of the amplifier, the auto-transformer step-up may be made very high without getting distortion and consequently the low microphone current for the plate circuit allows the microphone output to be comparatively small although due to this high transformer voltage step-up, the amplifier output is very large.

I claim:

1. In combination: a microphonic transmitter; an audio frequency amplifier connected therewith; and an energizing circuit for the microphone in series with the plate circuit of the amplifier.

2. In combination: a microphonic transmitter; an audio frequency amplifier connected therewith; and an energizing circuit for the microphone in series with the plate circuit of the amplifier and a substantial series resistance.

3. In combination: a microphonic transmitter; an audio frequency amplifier connected therewith; and an energizing circuit for the microphone in series with the plate circuit of the amplifier and a resistance of the order of 1000 ohms.

4. In combination: a microphonic transmitter; an audio frequency amplifier connected therewith; an energizing circuit for the microphone in series with the plate circuit of the amplifier and a substantial series resistance; and a resistance bridged across the terminals of the energizing circuit from the amplifier.

5. In combination: a microphonic transmitter; an audio frequency amplifier connected therewith; an energizing circuit for the microphone in series with the plate circuit of the amplifier and a resistance of the order of 1,000 ohms; and a resistance of the order of 2,000 ohms bridged across the terminals of the energizing circuit from the amplifier.

6. In combination: a microphonic transmitter; an audio frequency amplifier connected therewith; an energizing circuit for the microphone in series with the plate circuit of the amplifier and a substantial series resistance; and a by-passing condenser for the said resistance.

7. In combination: a microphonic transmitter; an audio frequency amplifier connected therewith; an energizing circuit for the microphone in series with the plate circuit of the amplifier and a series resistance of the order of 1,000 ohms; and a by-passing condenser of the order of 4 mfd. for the said resistance.

8. In combination: a microphonic transmitter; an audio frequency amplifier con-

5 nected therewith; an energizing circuit for the microphone in series with the plate circuit of the amplifier; a supplementary source of potential; and a switch to connect at will to the microphone of said secondary source of potential or the energizing supply from the amplifier without opening said plate circuit.

9. In combination: a microphonic transmitter; an audio frequency amplifier connected therewith; an energizing circuit for the microphone in series with the plate circuit of the amplifier and a substantial series resistance; a bridging resistance; a supplementary source of potential; a switch to connect at will to the microphone said secondary source of potential or the energizing supply from the amplifier; and means to short-circuit said bridging resistance when the supplementary source of potential is connected to the microphone.

In testimony whereof I affix my signature.
LINCOLN THOMPSON.
